WASHING MACHINE CABINET

Merlin S. Vincent, Newton, Iowa

Application April 19, 1937, Serial No. 137,643

1 Claim. (Cl. 220—10)

This invention relates to the structure of a domestic washing machine cabinet. For many years, washing machine tubs have been drawn steel, cup-like vessels with the top edge finished by an inverted U-shaped bead extending outwardly beyond the outside diameter of the tub. About three quarters of an inch under the top of this bead was rolled an inwardly extending horizontal U-shaped bead which served the dual purpose of splash ring and a shoulder upon which to rest the tub cover. These tubs were readily and easily made by the natural and normal manufacturing methods.

Such tubs could be easily surrounded by a skirt or cabinet because the plain cylindrical cabinet could be applied outside the tub as with its top edge extending under the top extending bead.

Although these tubs were entirely successful from the practical viewpoint, they were open to objections from the artistic viewpoint because the top of the cylindrically shaped washers as controlled by the tub showed a rather abrupt, cut-off, appearance. The washers would be much more artistic if the top or tub were a finished rounded curve.

As a result of this artistic criticism and in the face of increased manufacturing difficulties and costs, the tub manufacturers have recently been making what is known as a bullet nosed tub which has an inwardly curved top as illustrated in Figs. 2 and 3 of the drawings herewith. These tubs are becoming much in vogue.

It is common practice among the washing machine manufacturers to apply cabinets or skirts to the higher priced machines in their line of washers. Now with the new bullet nosed tubs, the application of such skirts is complicated and much more difficult.

It is to this problem that the present invention is directed. The particular object of the invention is to provide a cabinet structure for bullet nosed tubs that retains or enhances the artistic lines of the tub, this being comparatively easy to fabricate; and is structurally strong and durable.

Other objects will appear in the following description and accompanying drawings, in which Fig. 1 is a plan view of my complete washer cabinet;

Fig. 2 is a broken elevation view of the top of the cabinet;

Fig. 3 is an enlarged fragmental cross sectional view on the section lines 3—3 of Fig. 1, and

Fig. 4 is an enlarged fragmental cross sectional view on the section lines 4—4 of Fig. 2.

The numeral 10 shows the tub proper which as before stated is normally made of drawn steel, vitreous enamelled and numeral 11 shows the outwardly extending U-shaped bead on the top of the tub.

12 shows the cabinet member proper, a plurality of which in my design completely surround the tub 10. The numeral 13 shows an upright steel leg to which are attached the cabinet members 12.

It will be appreciated that the legs 13 support the tub, the washer mechanism and on their lower ends, mount the casters on which the complete machine is moved. In fact, the legs 13 are the main vertical structure members of my cabinet.

On top of the cabinet members 12 is a rubber ring member 14 which completely covers the upper edge of the cabinet sections 12 and is retained in position by the top bead 11 over the cabinet members 12 and attached to the leg members 13 are the concealed clip members 15, all attached to the leg members 13 by the screws 16. These screws 16, as illustrated, are of the self tapping variety. The finished strips 17 attach over the points of the cabinet members 12 completely covering these vertical edges and are snapped into position by the concealed snap fasteners 15.

It will be appreciated that these finished strip members may be put on after the cabinet has been completed and after it has been painted.

Further, that these strip members may be finished by electro-plating or any other desirable method of finishing to form a contrast with the finish on the cabinet members 12, thus obtaining artistic finish effects.

The numeral 18 shows a conventional tub cover which is finished on its peripheral edge by a rubber ring 19.

Although this is a normal conventional structure, attention is called to the fact that by my particular construction, the top line of the cabinet complete is made in a graceful curve and thus the artistic objection to the older constructions which were rather square at the top is effectively avoided.

The structure shown is the preferred embodiment of my invention, however, I do not wish to be limited to any particular structure, except as by the following claim.

I now claim as new:

In a washing machine tub construction in

55

combination, a sheet metal tub member having its rim portion turned inwardly and then outwardly circumferentially thereof to provide an outwardly open U-shaped channel about the tub rim, a plurality of sheet metal strips providing a skirt member extending about a substantial part of the side wall of said tub member and curved inwardly along its upper edge and disposed within said U-shaped channel, a resilient material disposed in said channel and enclosing the said edge portion of said skirt member, said

skirt strips having vertically extending side edges, the adjacent side edges of adjacent strips being disposed in edge to edge relation to one another, means securing said skirt strips rigidly together along said side edges, and a vertically extending stripping member extending along and over each joint between said side edges and covering said securing means, said stripping member being fastened to said skirt by concealed fastenings.
